INTERNAL CORNER CONNECTOR FOR A METAL CABINET

Eric Harry Lewer, Thorney Weir, Iver, Buckinghamshire,
England, assignor to Alfred Imhof Limited, London,
England, a company of Great Britain

Filed July 1, 1959, Ser. No. 56,617

Term of patent 14 years

(Cl. D54—1)

FIG.2.

FIG.1.

FIG.3.

FIG.4.

FIG. 1 is a front perspective view of an internal corner connector for a metal cabinet showing my new design;

FIG. 2 is a rear perspective view thereof;

FIG. 3 is a top plan view thereof; and

FIG. 4 is an elevational view taken from the right side of FIG. 3.

I claim:

The ornamental design for an internal corner connector for a metal cabinet, as shown.
